(57) **CLAIM**

The ornamental design for a fiber optic light source as shown and described.

DESCRIPTION

FIG. 1 is a front, right, and top perspective view of a fiber optic light source, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled "9" in FIG. 1; and,

FIG. 10 is an enlarged view of an encircled area labeled "10" in FIG. 2.

The broken lines depict portions of the fiber optic light source that form no part of the claimed design.

The dot-dash broken lines in FIGS. 1, 2, 9, and 10 framing portions of the claimed design that are illustrated for enlargements form no part of the claimed design.

1 Claim, 10 Drawing Sheets
